UNITED STATES PATENT OFFICE

102,084

DESIGN FOR A JUVENILE VEHICLE BODY

Herman L. Kraeft, Cleveland Heights, Ohio, assignor to The Murray-Ohio Manufacturing Company, Cleveland, Ohio, a corporation of Ohio

Application April 8, 1936, Serial No. 62,003

Term of patent 7 years

To all whom it may concern:

Be it known that I, Herman L. Kraeft, a citizen of the United States, residing at Cleveland Heights, in the county of Cuyahoga and State of Ohio, have invented a new, original, and ornamental Design for a Juvenile Vehicle Body, of which the following is a specification, reference being had to the accompanying drawing, forming a part thereof.

In the drawing, Fig. 1 is a perspective view of a juvenile vehicle body, showing my new design, and Fig. 2 is substantially a front eleva-

tion of said body, slightly in perspective by reason of relative elevation of the rear portion of the body.

The dominant features of the design are those shown in full line and shaded by stippling, particular reference being directed to the side and hood portions of the body; the seat being of substantially conventional shape.

I claim:

The ornamental design for a juvenile vehicle body, substantially as shown and described.

HERMAN L. KRAEFT.
